UNITED STATES PATENT OFFICE.

ARTHUR DUDLEY SOUTHAM, OF NEW YORK, N. Y.

OVERFEED-STOKER.

No. 820,528.

Specification of Letters Patent.

Patented May 15, 1906.

Application filed November 2, 1903. Serial No. 179,568.

To all whom it may concern:

Be it known that I, ARTHUR DUDLEY SOUTHAM, a subject of the King of Great Britain, residing in the borough of Manhattan, city, county, and State of New York, have invented certain new and useful Improvements in Overfeed-Stokers, of which the following is a specification, reference being had therein to the accompanying drawings, in which—

Figure 1 is a side elevation of the apparatus; Fig. 2, a longitudinal vertical sectional view thereof; Fig. 3, a horizontal sectional view, a portion of the apparatus being shown in plan; and Fig. 4, a transverse sectional view on the line IV IV of Fig. 2. Fig. 5 is a detail vertical sectional view of the means for adjusting the connection between the ram and the ram-operating lever.

This invention relates to that class of mechanical stokers in which small quantities of coal or coal-dust are periodically thrown or sprinkled over the surface of the fire and known as "overfeed" or "sprinkler" stokers.

The mechanism may for the purpose of this explanation be conveniently described under the following divisions: first, the reservoir, feeding-ram, and its mechanism; second, the sprinkler or shovel and its actuating mechanism.

Referring to the various parts by letters, N designates a reservoir or hopper for containing coal or coal-dust, and preferably provided with a suitable screen or grid at its lower end for the purpose of preventing large lumps of coal from entering the mechanism. The supply of fuel in this hopper may be replenished as and when required by hand or continuously through a suitable coal-chute. This hopper is mounted upon the upper side of a box or casing, which inclines slightly inward and downward, said hopper being secured thereto near the outer end thereof. The inner end of this casing is provided with a vertical wall or flange by which it may be secured to the front wall of a furnace by suitable bolts or other fastening means. The interior of this casing is divided horizontally by a feed-table T, the inner end of this table terminating short of the inner vertical wall of the casing, so that the fuel may be dropped off said table into the compartment below. The lower compartment is about half the length of the upper compartment and its

lower wall curves inward and downward to 55 form a curved bed on which the fuel drops from the feed-table. The upper compartment thus formed in the casing contains the feeding-ram R, and the lower compartment contains the pivotally-mounted sprinkler or 60 shovel S. In the front wall of the casing below the lower compartment is arranged the fire-door D, this door being adapted to be used when first starting the fire or when raking the same. It is also obvious that this 65 door may be used when stoking the fire by hand in the usual manner. Provision is made for regulating the admission of air over the fire by means of a register or damper F', forming a part of the fire-door. 70

I designates an inspection-door which closes the outer end of the upper compartment, said door being hinged at its upper edge and giving access to the feeding-ram, and D³ designates a sliding door mounted in 75 the lower wall of the lower compartment, which gives access to the shovel.

The feed-table T has on the part of its upper surface which is nearest the fire a number of jagged teeth t t, with their edges pointing toward the feed-ram, the purpose of which projections is to prevent the fuel from rolling or sliding down the surface except when pushed down by the action of the feeding-ram R, in the manner hereinafter 80 described. Alternately I may use one or more suspended check-arches C², as shown in Figs. 2 and 4. The presence of these teeth or a check-arch is important when using certain classes of coal, and more especially so when 90 the stoker is fixed to locomotive-boilers or on board ships where there is much vibration.

The fuel contained in the reservoir N is by the forward movement of the ram R periodically fed in predetermined quantities over 95 the edge of the table T and deposited on the bottom ledge at W in front of the sprinkler or shovel S during the period when the shovel is being drawn back away from the fire.

The feeding-ram R, which is supported on 100 both sides by the short projecting ribs P P, has a horizontal backward and forward sliding motion actuated and controlled by the arm L, which is pivoted at A. One end of this lever forms operative connection with 105 the feed-ram by means of the jaws J' J², located on the lower side of the feed-ram and engaging with the projection at the end of

the arm. The free end of this lever is provided at V with a roller which forms operative connection with the adjustable disks D' and D², hereinafter described. The face of the feed-ram is preferably concave, as shown in Fig. 3, and is provided with a sharp cutting edge to assist in breaking up any large lumps of coal.

The scraper-plate S P is pivoted at the top edge of the case and preferably has its lower edge beveled, so that the latter may rest evenly either on the upper surface of the dead-plate D P or the upper surface of the feed-ram R when the dead-plate is adjusted to its outer position, as hereinafter described. Now when the ram is drawn back a space is left in front of the concave face at R, which space is immediately filled with coal, this coal being in turn pushed along the table T and deposited in front on the shovel at W. The presence of the scraper-plate by preventing the coal on the surface of the ram from being carried back insures the fuel being pushed into the space in front of the ram-face. For the purpose of regulating the amount of feed by the ram the dead-plate D P is adjustable and may be made to advance and partially cover, and thereby render inoperative a greater or lesser portion of the space formed by the withdrawal of the ram. The front edge of this dead-plate is preferably beveled, thus tending to prevent any coal-dust from getting underneath it. Alternately I may vary the stroke of the ram R by varying the distance between the jaws J' and J², said jaws being adjustable for this purpose.

The suspended check-arch C² has its action controlled by the spiral spring s, attached to the vertical arm a, located outside the case, the tension of the spring being adjusted by the screw b. Its function is to check any fall of the fuel other than the amount fed by the action of the ram R. This falling or leaking of the fuel is sometimes liable to occur when the supply of coal in the reservoir falls below a certain level, especially if coal-dust be used and there is much vibration, as would be the case with railroad-locomotives. The elasticity of the spring s permits a swinging motion to the arch and allows the pushing through of the fuel when fed by the ram. The amount of fuel fed by the ram may also be approximately varied by altering the tension of the spring by means of the screw b. When there is much vibration and dry coal-dust is used, I may employ a second check-arch over t t.

The main shaft M, which rotates in the direction indicated by the curved arrow in Fig. 1, has keyed on it two disks D' and D². These disks have formed thereon a series of vanes or oblique blades v' v² v³ v⁴ and V' V² V³ V⁴, respectively, in such a manner that they cause the roller V, and consequently the arm

L, to oscillate to and fro, thereby operating the feed-ram. The vanes or blades may be made similar to the blades of a screw-propeller. Those affixed to the disk D' cause the arm L to advance the ram toward the fire, while the vanes on D² return the arm L toward the vanes on D', and so on alternately in like manner, thereby producing a continuous oscillation of the arm L. The amount of fuel thus fed and deposited at W by each oscillation of the ram can be very accurately regulated by varying the distance through which the ram travels, and I therefore make the effective throw of the blades adjustable, thereby increasing or decreasing the travel through which they operate the arm L. This may conveniently be done by adjusting the position of D' or D² by means of the lock-nuts x x.

The positions of the blades on the circumference of the disks D' and D² are adjusted and synchronized with reference to the arms or projections E' E² E³ E⁴ on the cam-wheel E, which operates the shovel S, so that the ram R is moved forward toward the fire at the same time as and while the shovel is being drawn back from the fire. This relative movement of the ram and shovel whereby the fuel is fed and deposited at the correct period is important to insure the efficient working of the machine.

The sprinkler or shovel S is preferably made of sheet-iron or sheet-steel, the front face being of an A or angular shape in plan view. The upper surface is entirely covered with a plate or sheet Y Y, slightly curved downward, so that any fuel accidentally falling thereon will roll down the incline to W.

The shovel S is suitably attached to the shovel-lever H', which passing through a slot at the bottom of the casing is pivoted on one or both sides of the casing at H and forms part of or is attached to the rocking lever A' B², also pivoted at H. Keyed to the main shaft M is the cam-wheel E, having arms E' E² E³ E⁴, all of unequal length.

C is a cylinder or case of uniform bore oscillating on the bearing G and containing an air-tight plunger or piston P² of suitable construction, with a piston-rod O attached thereto. The outer end of the piston-rod is pivoted to the upper end of the rocking lever A'. A spring F for propelling the shovel forward is coiled round the piston-rod and confined in the front part of the cylinder between the piston and the front cover K. The cover K is preferably made with a screw-thread, so that the initial compression of the spring F can be regulated by altering the position of the cover. The thread on the cover is broken or divided or the cover perforated, thus insuring the air in the front part of the cylinder being the same pressure as the surrounding atmosphere. I desire it under-

stood that the cylinder C may be pivoted in any desired manner to permit it to accommodate itself to the movement of the lever A². I find it advantageous in some constructions 5 of the machine to place the pivot G at the rear or outer end of the cylinder directly in line with the piston-rod O. This manner of pivoting the cylinder eliminates all side strains and holds the cylinder always in axial 10 alinement with the piston-rod.

Confined in the rear part of the cylinder by the back cover Q is the shorter spring B to assist in bringing the shovel to rest without shock or jar. The position of the spring B 15 may also be regulated by adjusting the back cylinder-cover Q, which is provided with a uniform screw-thread for that purpose and does not allow the air to escape. At A' is a small air-hole in such a position that any 20 vacuum created by the forward motion of the piston is destroyed on the piston passing that point. On the spring-propelled piston being released any sudden shock or jar to the mechanism is prevented by the cushioning 25 caused by the compression of air in the rear of the cylinder between A' and Q, assisted by the compression of the recoil-spring B. Now on the main shaft M being rotated in the direction shown by the arrow the lower end of 30 the rocking lever A² B², which is made of sufficient width to withstand wear, is carried back by one of the arms E of the sprocket-wheel. This motion of the rocking lever pulls back the shovel against the action of 35 the spring F, the extent of such motion being determined by the length of the particular arm in action. Simultaneously the feed-ram R has moved forward and deposited fuel 40 in front of the shovel at W. On the sprocket-wheel continuing to rotate the rocking lever is suddenly released at B². Consequently the shovel is quickly propelled forward by the backward movement of the spring-actuated piston. The amount of compression 45 given to the spring, and consequently the force of the impulse of the shovel, is determined by the length of the arms E' E² E³ E⁴, these being so arranged as to sprinkle the fuel over various sections of the fire-grate in 50 succession.

I claim—

1. In a mechanical stoker the combination of a casing adapted to be secured to the front wall of a furnace, a hopper at the upper outer 55 end thereof and in communication with the interior of said casing, a feed-table dividing said casing into an upper and a lower compartment the lower compartment being in communication with the furnace through an 60 opening in the front wall of the casing, a reciprocating feed-ram working on the feed-table, an adjustable dead-plate movable over the ram, a shovel in the lower part below the feed-table, means for pivotally mounting

said shovel, means for swinging said shovel 65 rearward, a spring for projecting the shovel forward.

2. In an overfeed-stoker the combination of a main reservoir, a casing located below said reservoir, a feed-table in said casing and partially dividing the same, a number of jagged teeth or projections on the upper surface of said table, a feed-ram adapted to slide on said feed-table, means for operating said feed-ram, means for regulating the throw of 75 the ram, an adjustable dead-plate above the ram, an inclined scraper-plate pivotally supported near the top of the divided casing its lower edge being beveled and resting on the dead-plate, a swinging shovel or sprinkler 80 below the feed-table, a spring for moving said shovel forward, and means for retracting the shovel.

3. In a mechanical stoker the combination of a hopper, a ram-compartment connected therewith and adapted to receive fuel therefrom, a ram therein, means for operating said ram, a feed-table in the bottom of said ram-compartment, a shovel-compartment below the ram-compartment and adapted to receive 85 fuel from the inner end of the feed-table, a scraper-plate mounted above the ram, its lower end extending near to the upper surface of the ram and preventing fuel moving rearward on the ram, a dead-plate above the 90 ram and adapted to slide under the scraper-plate a shovel in the shovel-compartment, and means for operating the shovel to force fuel 95 from the shovel-compartment.

4. In a mechanical stoker the combination 100 of a main fuel-reservoir, a casing below said reservoir, a feed-table located in said casing and dividing the same into a shovel-compartment and a ram-compartment and provided with upward-extending projections on its inner end, a ram above said table, means for operating said ram to force the fuel inward 105 on said table, and over the upward-extending projection thereon, an adjustable dead-plate above the ram at the outer end thereof, a scraper-plate pivotally supported above the dead-plate, its lower edge resting on said plate, a shovel mounted to move in the 110 shovel-compartment, and means for operating said shovel.

5. In a mechanical stoker the combination 115 of a hopper, a ram-compartment connected therewith, a ram in said compartment, means for operating said ram, a feed-table at the bottom of said ram-compartment, a shovel-compartment below the said table and adapted to receive fuel from the inner end thereof, a shovel in the shovel-compartment, means for pivotally mounting said shovel, a lever 120 connected to the shovel and movable therewith, means for moving said lever in one direction to swing the shovel rearward in its compartment, a cylinder pivotally mounted,

a piston therein, a piston-rod connected to said piston and to the lever, a spring within said cylinder and adapted to be compressed by the piston when the shovel is moved rearward, a buffer-spring in said cylinder said cylinder being formed with an aperture in its side wall whereby one end of the cylinder will be in open communication with the atmosphere when the shovel is in its rearward position.

6. In a mechanical stoker the combination of a hopper, a ram-compartment connected therewith, a ram in said compartment formed with a sharp cutting edge on its forward striking-face, means for operating said ram, a feed-table at the bottom of said ram-compartment, upward-extending teeth formed on said table near its inner end, a swinging yieldable check-arch above the feed-table, a shovel-compartment below the ram-compartment and receiving fuel from the inner end of the feed-table, a scraper-plate mounted above the ram, a shovel in the shovel-compartment, means for operating the shovel to force fuel from the shovel-compartment.

7. In a mechanical stoker the combination of a ram-compartment, a fuel-container connected therewith, a ram therein, means for operating the ram, a feed-table at the bottom of said ram-compartment, a shovel-compartment below the ram-compartment and adapted to receive fuel from the inner end of the feed-table, a shovel in the shovel-compartment its front edge being V-shaped in plan view and provided with a top plate whose forward edge extends beyond the front face of the shovel, said front edge being curved downward whereby said projecting top plate will prevent fuel being thrown back on the shovel, and means for operating the shovel to force fuel from the shovel-compartment.

8. In a mechanical stoker the combination of a casing adapted to be secured to the front wall of a furnace, a hopper at the upper outer end thereof and in communication with the interior of said casing, a feed-table dividing said casing into upper and lower compartments, the lower compartment being in communication with the furnace through an opening in the front wall of the casing, a reciprocating feed-ram working on the feed-table, an adjustable dead-plate movable over the ram, a scraper-plate adapted to work on the dead-plate, a shovel in the lower compartment below the feed-table, and means for pivotally mounting said shovel, means for swinging said shovel rearward, a spring for projecting the shovel forward, and means for providing an air-cushion to bring the shovel to a stop without a jar.

9. In a mechanical stoker the combination of a casing adapted to be secured to the front wall of a furnace, a feed-hopper in communication with the upper outer end of said cas-

ing, a feed-table dividing said casing into an upper and a lower compartment, the lower compartment being in communication with the furnace through an opening in the front wall of the casing, a reciprocating ram mounted on the feed-table, means for reciprocating said feed-ram, a swinging shovel mounted in the lower compartment, means for forcing said shovel rearward, a cylinder provided with an air-release hole or port, a piston therein, and means operatively connecting said piston to the shovel whereby when the shovel is moved rearward the spring will be placed under tension, means for providing a cushion to receive the piston when the spring is released to swing the shovel forward, and a cushioning-spring in the cylinder to receive the impact of the piston.

10. In a mechanical stoker the combination of a casing adapted to be secured to the front wall of a furnace, a feed-hopper in communication with the outer upper end of said casing, a feed-table dividing said casing into an upper and a lower compartment, the lower compartment being in communication with the furnace through an opening in the front wall of the casing, a reciprocating feed-ram mounted on the feed-table, means for reciprocating said feed-ram, an adjustable dead-plate movable over the outer end of said ram, a scraper-plate pivoted in the top of the casing and inclining inward and downward, its lower edge resting on the dead-plate, a swinging shovel mounted in the lower compartment, means for forcing said shovel rearward, a cylinder, a piston therein, a spring interposed between said piston and one end of the cylinder, and means operatively connecting said piston to the shovel whereby when the shovel is moved rearward the spring will be placed under a tension, means for providing a cushion to receive the piston when the spring is released to swing the shovel forward, a door closing the outer end of the upper compartment and a door in the bottom of the lower compartment.

11. In a mechanical stoker the combination of a casing adapted to be secured to the front wall of a furnace, a feed-hopper in communication with the upper outer end of said casing, a feed-table dividing said casing into an upper and a lower compartment, the lower compartment being in communication with the furnace through an opening in the front wall of the casing, teeth or projections on the upper surface of said table near the front end thereof to retard the movement of the fuel, a reciprocating feed-ram mounted on the feed-table, means for reciprocating said feed-ram, a swinging shovel mounted in the lower compartment, means for forcing said shovel rearward, a cylinder, a piston therein, a spring interposed between said

piston and one end of the cylinder, means operatively connecting said piston to the shovel whereby when the shovel is moved rearward the spring will be placed under tension, and means for providing a cushion to receive the piston when the spring is released to swing the shovel forward.

In testimony whereof I hereunto affix my signature, in the presence of two witnesses, this 8th day of October, 1903.

ARTHUR DUDLEY SOUTHAM.
